[57] CLAIM

The ornamental design for a mechanic's creeper, as shown and described.

DESCRIPTION

FIG. 1 is a top perspective view, on a reduced scale, of a mechanic's creeper, showing my new design;

FIG. 2 is a top plan view;

FIG. 3 is a front elevational view thereof, the rear elevational view being a mirror image;

FIG. 4 is a left-side elevational view;

FIG. 5 is a right-side elevational view; and,

FIG. 6 is a bottom plan view thereof.

FIG. 1

FIG. 4

FIG. 5

FIG. 2

FIG. 3

FIG. 6
